PRODUCT DELIVERY DOOR FOR VENDING MACHINES

Mark Levine, Bethpage, N.Y., assignor to Continental Vending Machine Corp., Westbury, N.Y.
Filed Dec. 18, 1962, Ser. No. 245,495
8 Claims. (Cl. 312—35)

The present invention relates to product delivery doors used in hot and cold food and other types of vending machines. The invention does not relate to vending machines in which product delivery doors are neither used nor desired.

Illustrative of the vending machines in which such doors are conventionally used are those which either heat or refrigerate, store and vend food products of various kinds and in various forms of packaging, such as platters or trays of hot foods, and dishes of ice-cream and other frozen or chilled desserts. In such machines delivery doors are installed for various purposes, not the least of which is to serve as heat transfer barriers. The problem of heat transfer is essentially non-existent in vending machines which store and sell merchandise at ambient temperatures such as machines which vend cigarettes, packaged candies, and personal articles.

Another problem with which vending machine operators must contend is the problem of theft. Some members of the general public view vending machines as a personal challenge to their ingenuity, and they endeavor by any and all means to effect unauthorized removal of merchandise. These individuals have used their hands and a great variety of ingeniously contrived instruments, tools and devices to "beat" the vending machines. Product delivery doors provide at least one means of thwarting such pretty thievery.

It is the principal object of this invention to provide a product delivery door for vending machines of the character described, said product delivery door being adapted to protect the merchandise against theft, to serve as a heat-transfer barrier in order to assist maintaining the merchandise at predetermined temperatures, and to prevent entry of foreign matter which might contaminate the merchandise.

The invention will herein be described with respect to a hot food vending machine, but it will be understood that this is purely illustrative and is not intended to limit the application of the invention to this particular type of machine. The invention is applicable to all vending machines in which product delivery doors are used.

In the illustrated embodiment of the invention, as related to hot food vending machines, the following functions or operations occur in the sequential order given:

(1) The product delivery door is maintained in latched or locked condition during the food pre-heating cycle.

(2) The product delivery door is unlatched or unlocked after the food attains serving temperature and is adapted for vending.

(3) The product delivery door is temporarily latched or locked during the very short period in which a selected food product is ejected from the heating oven or section into the delivery tray.

(4) The product delivery door is unlatched or unlocked following said temporary latching or locking period, and it may now be opened (raised) to provide access to the delivered food product.

An important feature of this invention, as hereinabove indicated, is its prevention of unauthorized removal of merchandise. This feature is attained by means of a delivery tray which delivers the purchased product by tilting from one position to another. Its delivery position is such that it automatically closes off the storage section behind or above it, and prevents unauthorized

2

access to the inside of the machine. In the illustrated form of the invention, the delivery tray is actuated by the product delivery door. When the door is opened, the delivery tray is tilted, thereby permitting removal only of the purchased product.

In the illustrated form of the invention, the delivery tray is actuated by the product delivery door. When the door is opened, the delivery tray is tilted, thereby permitting removal only of the purchased product.

10 In the illustrated form of the invention, there are three food storage and heating sections disposed in side-by-side relation. The tiltable product delivery tray is centrally situated to receive and discharge food products stored in the middle section. Non-tiltable delivery trays are situated on opposite sides of the tiltable tray to deliver products stored in the two end sections.

15 The details of the invention are illustrated in the accompanying drawing in which:

20 FIGURE 1 is an inside view of the product delivery door, including operating mechanism and product delivery tray, shown installed in a hot food vending machine.

FIGURE 2 is a vertical section therethrough on the line 2—2 of FIGURE 1, showing the product delivery tray in lowered position, the product delivery door being 25 also in lowered or closed position.

FIGURE 3 is a fragmentary enlarged section on the line 3—3 of FIGURE 1.

FIGURE 4 is an enlarged fragmentary section on the line 4—4 of FIGURE 1.

30 FIGURE 5 is an enlarged fragmentary section on the line 5—5 of FIGURE 1.

FIGURE 6 is an enlarged fragmentary section on the line 6—6 of FIGURE 1.

FIGURE 7 is a vertical sectional view resembling that 35 of FIGURE 2, but showing the product delivery tray in elevated, delivering position.

FIGURE 8 is a front view of the delivery ends of the three food storage compartments situated behind the product delivery door.

40 FIGURE 9 is a fragmentary front view of a vending machine in which the present invention is installed, showing the product delivery door in lowered or closed position.

The drawings illustrate a hot food vending machine 8 45 having a product delivery ledge 9 projecting forwardly from its front wall. Immediately above said ledge is a product delivery door 10 which is a lift door, being mounted for vertical sliding movement between a front door plate 11 and a pair of guide rails 12. The door may 50 be made of a sheet or plate of transparent plastic material, thereby serving the dual function of an insulator and a window.

It will be understood that the product delivery door 10 is a manually operated door, being adapted for lifting by the customer to open position to provide access to the purchased product. When released by the customer after the purchased product is removed, it will automatically drop to its closed position.

Secured to product delivery door 10 is a latch bracket 60 13 which moves integrally with the door. The upper end of said latch bracket is bent over at a 90-degree angle to form a latch bar 14, which is adapted to engage a notch 15 in a locking bracket 16. This locking bracket is mounted for arcuate motion about a fixed horizontal pin 65 17, and it is held in place on said pin by any conventional fastening or locking means.

It will now be observed that locking bracket 16 is a bell crank, notch 15 being formed in its vertical component, and a link 18 being pivotally connected to its horizontal component. This link is connected to the plunger 70 of a solenoid 19 which is rigidly mounted on a support plate 20 secured to a frame 20a in the vending ma-

chine. It will be apparent from the foregoing that locking bracket 16 is in locking engagement with the locking bar 14 when the solenoid is energized and said locking bracket occupies the position which is illustrated in FIGURE 1 of the drawing. This involves a counterclockwise movement of said locking bracket as viewed in said FIGURE 1. It would require a clockwise movement of said locking bracket to cause it to disengage locking bar 14, and such clockwise movement would occur when the solenoid is disengaged.

Also mounted on support plate 20 is a switch 21 having an actuating arm or lever 22. It will be noted that switch arm 22 is engageable with locking bar 14 when the product delivery door is in closed position as illustrated in FIGURE 1. When the door is raised to open position locking bar 14 disengages switch arm 22 and the switch is thereby actuated. Whether it is a normally open or normally closed switch depends upon the circuitry which it controls but this is not a part of the present invention and the circuitry is accordingly neither shown nor claimed.

A bracket 23 of horizontal bar 24 moves integrally with the product delivery door when said door is moved vertically either upwardly to open position or downwardly to closed position. Bar 24 is rigidly secured to said door by means of vertical side frame frame channels 25. Door 10, side frame channels 25, horizontal bar 24 and bracket 23 constitute a single rigid assembly. It will be observed in FIGURE 6 that the plastic plate which constitutes door 10 is held within said side frame channels 25 which serve as its vertically extending side rails.

Bracket 23 is provided with side flanges 27 which support a cross pin 26. Pivotally mounted on said cross pin is a cam assembly 29 which is best shown in FIGURE 2. This cam assembly comprises a bracket 29a having a cam shaped element or elements 29b formed thereon at its upper end. It is the lower end of said bracket 29a which is pivotally mounted on cross pin 26. The upper end of bracket 29a bears against a fixed cross pin 30. The cam formations 29b bear against a product delivery tray 31 which is pivotally secured to the door body 33 by means of a hinge pin 32.

Remembering that bracket 23 is rigidly connected to the product delivery door 10 by means of bar 24 and side frame channels 25, it will be understood that when said door is manually lifted to open position, cam assembly 29 will also be elevated. However, it will also swing arcuately in counterclockwise direction about pin 26 as viewed in FIGURE 2. The upper end of bracket 29a will thereupon ride up on support pin 30 while cam formations 29b will cam the product delivery tray 31 to its upper, product-delivery position. Tray 31 moves upwardly and arcuately in clockwise direction about pin 32 as viewed in FIGURE 2.

It will now be noted that product delivery tray 31 comprises two sections 31a and 31b which are joined to each other at an angle of approximately 150 degrees. This is not a critical angle, but simply indicates an acceptable relationship between these two sections for the purpose shortly to be described. Interrupted lines 31c represent a food product or package which is to be delivered by means herein disclosed. Section 31b of delivery tray 31 is tilted downwardly and rearwardly from the delivery opening. This is the position of the delivery tray prior to raising the delivery door to open position. When the door is raised to its open position, as hereinabove described, delivery tray 31 will swing in clockwise direction as viewed in FIGURE 2, and section 31b thereof will thereupon assume either a horizontal position or a slightly tilted position in the opposite direction relative to the horizontal position from that shown in FIGURE 2. In other words, section 31b of the delivery tray will be tilted forwardly and rightwardly as viewed in FIGURE 2, its rear portion (left portion as viewed in FIGURE 2) being elevated above its

forward portion (right portion as viewed in FIGURE 2). This will facilitate delivery of the food package.

At the same time, section 31a of the delivery tray will be swung upwardly to a predetermined elevated position, at which point it will serve as a theft barrier, preventing unauthorized removal of other merchandise stored within the machine.

A vertical lift guide tube 34 is welded or otherwise secured to bracket 23. It will be recalled that bracket 23 is connected to the product delivery door by means of horizontal bar 24 and vertical channel frames 25. Consequently, lift guide tube 34 will move integrally with the product delivery door as said door is moved to either open or closed position. Tube 34 extends through a pair of bushings 34a and 34b on a support bracket 34c. The support bracket is secured by conventional means to the frame of the machine, and it will therefore be understood that it is by this means that the lift guide tube 34 is itself guided for vertical axial movement and said tube, in turn, is thereby also able to guide the product delivery door in its vertical movement from closed to open position, and back.

A pin 35 extends through guide tube 34 and is held in place therein by means of cotter pin 36. This is best shown in FIGURE 3. Pin 35 is engaged by a pair of slotted links 39 and 41. More specifically, these slotted links 39 and 41 are pivotally mounted on bracket 34c by means of pins 42 and 43, respectively. Slot 38 in link 39 and slot 40 in link 41 intersect to accommodate pin 35 above-mentioned. It will now be apparent that when the product delivery door is either raised or lowered, together with lift guide tube 34, pin 35 will cause pivotal movement of the two links 39 and 41.

Secured to the far end of the two links 39 and 41 is a tension spring 46. More precisely, the ends of said tension spring are wrapped around pins 44 and 45, respectively, of links 39 and 41. The operation of this spring will now be described.

The starting position is illustrated in FIGURE 1, wherein the product delivery door is in its lowered or closed position. As the door is raised to its upper or open position, tube 34 will move upwardly with it and links 39 and 41 will pivot upwardly to the extent of shortening the distance between pins 44 and 45. This will reduce the tension in spring 46.

After the product delivery door has reached the top of its stroke, and the food product is removed from the machine, the door is released by the customer and it thereupon descends under its own weight or under spring tension, or by any other conventional means which may be designed into the machine. As the door descends, so will guide tube 34, thereby causing links 39 and 41 to pivot downwardly to their relative positions in FIGURE 1. The distance between pins 44 and 45 will now increase, thereby increasing the tension in spring 46. This will serve to cushion and retard the downward movement of the door, thereby preventing damage to the door or any of its associated parts, and also preventing injury to the customer. Injury has been known to occur in other machines when the door is inadvertently or accidentally released, while the customer's hand is still inserted into the door opening to remove the purchased product.

The present invention is illustrated in connection with a hot food vending machine in which there are three food storage and heating compartments situated behind the product delivery door. This, of course, is purely illustrative, as will readily be understood. Associated with these three food compartments are suitable product dispensing means which may be conventional or not, as desired. In any event, such dispensing means are not disclosed in the present application and are not claimed herein. For present purposes it suffices to say that the product dispensing means delivers the products stored in any of the three compartments through a swinging exit door 50 which is located behind the product delivery tray 31. As each product issues through door 50, it enters upon the

product delivery tray 31 when said tray is in its relatively prone position shown in FIGURE 2. When the product delivery door is raised to open position, as above described, the product delivery tray 31 will tilt to its FIGURE 7 position and thereby deliver the vended product. When the product delivery tray is elevated or tilted to its included delivery position of FIGURE 7, it blocks access through the exit door to any of the food storage compartments in the machine. To insure against unauthorized access to the inside of the machine through said exit door, the food delivery tray is provided with a pair of side wings or flanges 52 to preclude such access.

The foregoing is illustrative of the preferred form of this invention, and it will be understood that this form may be modified and other forms may be provided within the broad spirit of the invention and the broad scope of the claims. For example, it will be clearly understood that the particular type of mechanical linkage between the product delivery door and the product delivery tray is not critical. What is essential is that the product delivery tray tilt when the door is opened in order to deliver a selected and dispensed product and, at the same time, block unauthorized access to the inside of the vending machine. The precise latching or locking means on the product delivery door is not critical. What is required is any latching or locking means which will prevent unauthorized opening of the product delivery door.

What is claimed is:

1. Product delivery means for vending machines having at least one product storage compartment, and product dispensing means associated therewith, said product delivery means comprising a product delivery door and a product delivery tray, said door being movable between closed and open positions, said tray being movable between a product receiving position in which the tray is adapted to communicate with the product storage compartment and product dispensing means to receive a dispensed product, said product receiving position of said tray corresponding to the closed position of said door and said product delivery position corresponding to the open position of said door, a mechanical linkage operatively connecting said product delivery tray with said product delivery door, said mechanical linkage comprising a bracket connected to said door and a cam connected to said bracket and engaging said tray, whereby movement of the door from the closed to the open position causes the cam means to cam the tray from product receiving position to product delivering position, this being a tilted position wherein the tray serves as a barrier preventing unauthorized access to said product storage compartment and said product dispensing means.

2. Product delivery means for vending machines having at least one product storage compartment, and product dispensing means associated therewith, said product delivery means comprising a product delivery door and a product delivery tray, said door being movable between closed and open positions, said tray being movable between a product receiving position in which the tray is adapted to communicate with the product storage com-

partment and product dispensing means to receive a dispensed product, a mechanical linkage operatively connecting said product delivery tray with said product delivery door to cause said tray to move into its said product delivering position when the door is moved to open position, and whereby said tray is caused to move into product receiving position when the door is moved to closed position, said product delivering position of said tray being such as to block access to such product storage compartment and product dispensing means to prevent unauthorized product removal, and said product delivery door being vertically movable between its closed and open positions and manually movable in upward direction into open position and downwardly movable by gravity to closed position.

10 3. Product delivery means in accordance with claim 1, wherein a locking mechanism is connected to the door to prevent unauthorized opening thereof, said locking mechanism comprising a solenoid-actuated latch.

20 4. Product delivery means in accordance with claim 1, wherein the solenoid-actuated latch comprises a locking bracket connected to the door, a keeper for said bracket, said keeper comprising a notched bell crank, and a solenoid operatively connected to said bell crank, whereby energization of the solenoid causes the keeper to engage the bracket and whereby de-energization of the solenoid causes the keeper to disengage the bracket.

25 5. Product delivery means in accordance with claim 2, wherein spring means are provided to cushion the downward movement of the product delivery door to closed position.

30 6. Product delivery means in accordance with claim 2, wherein the cushioning means are operatively connected to the mechanical linkage between the product delivery door and the product delivery tray, said cushioning comprising a vertically movable member which is connected to the door, a pair of toggle bars connected to said vertically movable member and a spring interconnecting said toggle bars.

35 7. Product delivery means in accordance with claim 2, wherein a locking mechanism is connected to the door to prevent unauthorized opening thereof, said locking mechanism comprising a solenoid-actuated latch.

40 8. Product delivery means in accordance with claim 2, wherein the solenoid-actuated latch comprises a locking bracket connected to the door, a keeper for said bracket, said keeper comprising a notched bell crank, and a solenoid operatively connected to said bell crank, whereby energization of the solenoid causes the keeper to engage the bracket and whereby de-energization of the solenoid causes the keeper to disengage the bracket.
